UNITED STATES PATENT OFFICE

2,166,828

ALTERNATING CURRENT CIRCUIT
INTERRUPTERFred L. Stone, Schenectady, N. Y., assignor to
General Electric Company, a corporation of
New York

Application June 28, 1938, Serial No. 216,271

6 Claims. (Cl. 200—147)

My invention relates to circuit interrupters, more particularly to alternating current circuit interrupters, and has for its principal object the provision of an improved alternating current arc interrupter that is effective to interrupt arcing without causing appreciable extension or lengthening of the arc beyond the arc gap determined by separation of the interrupter electrodes or contacts.

10 It is well known that the arc energy increases with increase in the length of the arc, and that such increase in energy is often undesirable since it requires the dissipation of a considerable amount of heat during the arc-interrupting operation. However, this method of arc interruption is commonly used in the conventional magnetic blow-out type breaker since lengthening and subsequent cooling of the arc within the arc chute are also relied upon to increase the arc 20 resistance so that interruption can take place at a current zero. In this type of breaker, a blow-out coil in series with the circuit to be interrupted is usually employed so that the alternating magnetic blow-out flux causes continuous 25 transverse movement of the arc through the chute. Accordingly, the arc is extended or looped into the chute so as appreciably to increase the arc length and, consequently, the heat to be dissipated.

30 In accordance with the present invention, an alternating current arc is subjected to a substantially constant and direct or unidirectional blow-out flux whereby the arc, instead of being extended or moved continuously in a transverse direction, is subjected to a force tending to oscillate it within comparatively narrow limits at a rate corresponding to the frequency of the arc current. If not interrupted at the first current zero due to the presence of a large and constant 35 blow-out flux, the rapid oscillation of the arc and arc roots across the contact surfaces serves to deionize the arc and to facilitate interruption within substantially the arc length determined by the gap formed by the separated interrupter 40 electrodes, or contacts.

45 My invention will be more fully set forth in the following description referring to the accompanying drawing, and the features of novelty which characterize my invention will be pointed out with particularity in the claims annexed to and forming a part of this specification.

50 Referring to the drawing, Fig. 1 is a partly diagrammatic view of an alternating current circuit breaker embodying the present invention, Fig. 2 is an end view of the breaker shown in Fig. 1,

and Fig. 3 is a side elevational view partly broken away of another form my invention may assume.

In the interrupting arrangement shown by Figs. 1 and 2 a load circuit 1 for supplying current to apparatus, such as a motor 2, is energized from an alternating current power circuit indicated at 3. A circuit breaker embodying the present invention is indicated at 4 for controlling the load circuit 1, and comprises in the present instance a pair of relatively movable contacts 5 and 6 operable within an insulating housing 7 that is open at the opposite ends thereof as illustrated. The load circuit 1 is suitably connected to the breaker contacts by the terminals 4'. 10

The contacts 5 and 6 in the specific arrangement shown are arcuate in form and are adapted to engage in abutting contact at the surfaces 5' and 6' respectively in the closed circuit position. In the open circuit position shown the fixed contact 5 and the coacting movable contact 6 form 20 with the insulating housing 7 a pair of oppositely extending diverging arc passages extending from the arc gap defined by the contact surfaces 5' and 6'. Accordingly, when the breaker is opened by downward movement of the contact 6 to the 25 position shown, an arc is formed at the central or narrowed part of the arc passage.

For the purpose of interrupting the arc in the manner above described, a magnet core 8 having depending pole pieces 9 extending along the insulating housing 7 at opposite sides of the arc gap is provided with an energizing coil 10 that is connected in any suitable manner with a direct current source. In the present instance, the coil 10 is shown diagrammatically as energized from 35 the main alternating current power circuit through a full wave rectifier 11. The flux between the pole pieces 9 across the arc gap 5'—6' is therefore direct or unidirectional in character as contrasted with the alternating arc current 40 and furthermore is not dependent on the magnitude of the arc current. This is an advantage where the arc current is weak. 45

Accordingly, when the alternating current arc is formed the unidirectional flux tends to oscillate 50 the arc as long as it persists back and forth within the arc passage between the contacts 5 and 6. The rate of oscillation is of course dependent on the frequency of the circuit to be interrupted. Coincident with the oscillation of the arc and 55 the deionizing tendency, the arc roots themselves are rapidly moved back and forth along the conducting surfaces of the contacts 5 and 6 so that the formation of metallic vapor is minimized. This is an important consideration since inter- 55

ruption of the arc is made more difficult by the presence of a large amount of metallic vapor caused by a stationary arc root. Rapid oscillation of the arc roots also serves to increase the life of the contacts.

The deionizing effect of rapidly oscillating the arc by a substantially constant and steady flux within predetermined limits is an important factor in causing interruption of the arc although other factors likewise tending to cause extinction of the arc are undoubtedly present. The above deionizing effect is of course enhanced by the presence of the strong blow-out flux when the arc current passes through the zero value. This is not the case in the conventional magnetic blow-out breaker.

It will be observed that lengthening of the arc is limited in a positive manner by the arc gap defined between the contacts 5 and 6 within the insulating housing. Even assuming appreciable amplitude of oscillation within the arc passage 7', it will be apparent that the actual arc length is not at any time greatly in excess of the minimum arc gap. Furthermore, the well known tendency of the arc to loop outwardly along a horn gap is counteracted at the subsequent half cycle when the arc is subjected to a force causing it to move in the opposite direction. This serves, as above pointed out, to minimize the arc energy generated during the interrupting operation and hence to facilitate interruption.

Movement of the contact 6 can be effected in any suitable manner, a simple arrangement being diagrammatically illustrated for this purpose. A closing solenoid 12 is connected through an operating rod 13 and a resilient or wipe connection at 14 to the contact 6. The solenoid 12 can be energized from the source 3 through a push button control 15 to close the breaker, the same being held in closed circuit position by a latch and detent 16-17. In case of overload on the load circuit 1 a current transformer 18 causes energization of the trip coil 19 so as to actuate the releasing latch 16 whereupon the contact 6 moves downward to the open circuit position shown.

Fig. 3 illustrates a simplified form of the alternating current arc interrupter wherein the constant unidirectional magnetic flux is produced by a permanent magnet, preferably of the precipitation hardened alloy type. This type of permanent magnet has a comparatively large magnetomotive force and is particularly effective at low values of the arc current, as contrasted with the conventional magnetic blow-out air circuit breaker wherein the blow-out flux is obviously dependent on the magnitude of the current to be interrupted. Furthermore, by using a permanent magnet of this type, a comparatively compact alternating current arc interrupter, not heretofore available, is provided.

In the specific arrangement shown, the electrode or contact structure proper may be substantially the same as described in connection with Figs. 1 and 2. In this case, however, a permanent magnet 20 having depending pole pieces 21 extending along opposite sides of the arc gap between the contacts 5 and 6 is provided. A permanent magnet of the character above described is effective to project a strong, constant unidirectional flux across the arc gap at all values of the arc current so that the arc is oscillated in

the manner above described at a rate corresponding to the frequency of the arc current.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An alternating current arc interrupter comprising arc forming means for defining an arc gap, means for subjecting the arc in said gap to a unidirectional flux whereby said arc tends to oscillate with respect to said gap at a rate corresponding to the frequency of the arc current, and means for maintaining said arc in said gap substantially at constant length.

2. An alternating current arc interrupter comprising arc forming means for defining an arc gap of substantially predetermined length, means for subjecting the arc in said gap to a substantially constant unidirectional flux whereby said arc tends to oscillate in said gap at a rate corresponding to the frequency of the arc current, and means for restricting said arc to a length not appreciably in excess of the width of said gap.

3. An alternating current arc interrupter comprising arc forming means for defining an arc gap, a magnet for projecting a substantially steady, constant and unidirectional flux across said gap whereby said arc and the roots thereof tend to oscillate within said gap at a rate corresponding to the frequency of the arc current, and means for maintaining said arc in said gap substantially at constant length.

4. An alternating current arc interrupter comprising coacting electrodes between which an arc is formed upon opening of the circuit, said electrodes being generally of mutually convex form so as to define diverging gaps at opposite sides thereof, and magnetic means for projecting a substantially constant unidirectional flux across the minimum gap whereby said arc and the roots thereof tend to oscillate with respect to said minimum gap at a rate corresponding to the frequency of the arc current, said unidirectional flux being related to said electrodes so that said arc is restricted to a length not appreciably in excess of the width of said gaps.

5. An alternating current arc interrupter comprising coacting electrodes for defining an arc gap, magnetic means including a source of substantially constant magnetomotive force for projecting a unidirectional flux across said gap so that said arc is acted upon by an oscillating force, said flux being of blow-out magnitude in said gap when the arc current passes through the zero value, and means for restricting said arc to a length not appreciably in excess of the width of said gap.

6. An alternating current arc interrupter comprising a pair of elongated contacts separable transversely of the longitudinal axes thereof to form an arc gap, and a permanent magnet having poles extending along opposite sides of said gap for projecting a constant unidirectional flux across said gap whereby said arc is subjected to an oscillating force tending to prevent appreciable lengthening thereof.
